[57] CLAIM

The ornamental design for a gas discharge lamp ballast, as shown and described.

DESCRIPTION

FIG. 1 is a front and upper right perspective view showing our design;

FIG. 2 is a rear view;

FIG. 3 is a bottom plan view; and,

FIG. 4 is a left side elevation view.

The broken line showing is included only for the purpose of illustrating environmental elements only and forms no part of the claimed design.
